DESIGN FOR A LAMP

Ashton B. Collins, Birmingham, Ala.

Application January 3, 1939, Serial No. 82,125

Term of patent 7 years

To all whom it may concern:

Be it known that I, Ashton B. Collins, a citizen of the United States, residing at Birmingham, in the county of Jefferson and State of Alabama, have invented a new, original, and ornamental Design for a Lamp, of which the following is a specification, reference being had to the accompanying drawing, forming part thereof.

Figure 1 is a perspective view of a lamp showing my new design.

Figure 2 is a front elevational view thereof with the shade and bulb omitted.

Figure 3 is a section on line 3—3, Figure 2.

I claim:

The ornamental design for a lamp, as shown and described.

ASHTON B. COLLINS.
